UNITED STATES PATENT OFFICE.

HOWELL W. SOUDER, OF TAMAQUA, PENNSYLVANIA.

ELECTRIC SIGNALING APPARATUS.

SPECIFICATION forming part of Letters Patent No. 642,379, dated January 30, 1900.

Application filed August 28, 1899. Serial No. 728,677. (No model.)

To all whom it may concern:

Be it known that I, HOWELL W. SOUDER, a citizen of the United States of America, and a resident of Tamaqua, county of Schuylkill, State of Pennsylvania, have invented certain new and useful Improvements in Electric Signaling Apparatus, of which the following is a specification.

My invention relates to electric signaling apparatus generally, and more specifically consists of an improved block-signal apparatus capable of use on single-track electric railways and especially designed to guard both ends of the sections of track between turnouts.

The broad idea of my invention is to have a signal at the end of each section of track, or near the end of each section of track, the two signals for each section being operated simultaneously and shifted to "danger" when a car goes onto that section and shifted to "safety" when a car goes off the section. At the same time that the signals on the said section are operated those on adjacent ends of the neighboring sections of track are illuminated, so that the motorman can tell what the condition of the signals on the section ahead of him is, and thereby determine whether to stay on the turnout between said sections or to proceed on his way.

In carrying out the broad idea of my invention numerous different forms of apparatus may be employed; but the preferred form of apparatus, with one or two modifications, is illustrated in the accompanying four sheets of drawings, in which—

Figure 1 is a diagrammatic view of a single-track road with my signals and their operating-circuits in position. Fig. 2 is a half-elevation and half-section of a signal-lantern with the preferred form of signal apparatus therein. Fig. 3 is a side elevation of the said apparatus removed from the signal-lantern. Fig. 4 is a plan view, and Fig. 5 is a side elevation and partial section, of the preferred form of contact-making or current-supplying device for operating the signal. Fig. 6 is a cross-section of the same. Figs. 7 and 8 are cross-sections of modifications.

Throughout the drawings like reference-figures refer to like parts.

A single-track road, such as represented

in Fig. 1, has a number of turnouts 1, 3, 5, 7, 9, and 11 connected by a series of single-track sections 2, 4, 6, 8, and 10. These sections are shown broken away in the middle to indicate that they are of much greater length than the turnouts, said sections being of course sometimes a mile in length, while the turnouts do not average more than 60 a hundred feet in length. The trolley-wire 12 furnishes the power to drive the electric cars and all the current to operate my system of signals. For the latter purposes it has a series of current-supplying devices attached to it opposite the ends of each section of track, as shown at 2^a 2^b, 4^a 4^b, 6^a 6^b, 8^a 8^b, and 10^a 10^b. From these current-supplying points feed-wires run to the signal-circuits 13, 14, 15, 16, 17, 18, and 19. These 70 signal-circuits are grounded at each end of each circuit and the current-supply is delivered to the central portion of the circuit, where it splits and reaches the ground by passing through the two halves of the circuit. Thus 75 one ground connection of the circuit 13 is shown at 20, and one ground connection of the circuit 14 is shown at 21. The ground connections of the circuit 15 are shown at 22 and 23, and those of the circuit 16 are shown at 24 80 and 25. The two ground connections for the circuit 17 are shown at 26 and 27, one of those for circuit 18 is shown at 28, and one of those for circuit 19 is shown at 29.

At or near the end of each track-section I 85 locate a signal apparatus, as indicated at 30, 31, 32, 33, 34, 35, 36, 37, 38, and 39, which consists of an automatically-shifting signal and a plurality of lamps for illuminating the same.

The details of the shifting apparatus and 90 connections I will describe hereinafter; but for the purposes of the present description will state that each signal-station contains a shifting apparatus operated by a solenoid and preferably two lamps for illuminating the 95 same, the shifting apparatus being represented in Fig. 1 by the small rectangle within the larger rectangle, which represents the lantern, and the two lamps being represented by small circles. The lamps and the solenoid 100 are so connected that in case of any one track-section, as section 6, the solenoid and one lamp in the signal apparatus at 34 and 35, located at or near the ends of the track-section,

are connected together, preferably in series, and from these signal-stations the circuit of the signal-wire 16 runs through an independent lamp in the signal-stations 33 and 36, located at or near the adjacent ends of the neighboring track-sections 4 and 8. In the same way the signal-circuit 15 of track-section 4 extends through the solenoid and one lamp in each of the stations 32 and 33, guarding the ends of that track-section, and then extends on through the independent lamp in each of the signal-stations 31 and 34, guarding the adjacent ends of track-sections 2 and 6. Similarly the signal-circuit 17 of track-section 8 extends through the lamp and solenoid in the signal-stations 36 and 37, guarding the ends of said track-section 8, and then extends on to the independent lamps in the stations 35 and 38, guarding the adjacent ends of the track-sections 6 and 10. The connection from each of the contact or current-supplying points 6^a and 6^b to the signal-circuit 16 is made at points intermediate of the signal-stations 34 and 35, corresponding to the ends of the track-section 6. In the same way the connections from all the other current-supplying points are made to the central portion of the signaling-circuits, so that whenever current is supplied it will reach the signal-circuit at a point such that the current must pass through two signaling-stations in each direction before reaching the ground.

I will now describe more in detail the features of the different pieces of apparatus which operate or are operated by the above-described electrical connections. Each signal consists of an ordinary signal-lantern 41, which may be attached to a trolley-pole by a bracket 40. (Shown broken away in Fig. 2.) Within this lantern is mounted the signaling apparatus, which consists, briefly, of a rotatable drum having alternate panes of red and colorless glass, a solenoid or other electric engine for giving partial rotation to said drum sufficient to shift the panes of glass from red to white, &c., two or more lamps within said drum, and electric connections for operating the electric engine and for lighting up the lamps. This apparatus is preferably mounted on a signal bed-frame 42, so that it may be slipped in and out of the lantern 41 as a whole when the electric connections are broken. On this bed-frame 42 are uprights 43 44, which support fixed hollow journals 45 and 46. On the journal 45 is a ratchet-wheel 47, having teeth provided with double faces 47^a 47^b. The upright 43 is continued on upward and supports solenoid 48, preferably made in double form, as shown in Fig. 3, and provided with a double core 49, from the lower cross-piece of which is pivotally supported the double feed-pawl and stop 50, which co-operates with the ratchet-wheel 47. This piece 50 has one finger 50^a operating as a feed-pawl, and one, 50^b, operating as a stop. Rigidly connected with the ratchet-wheel 47 is a rotatable drum 51, which is mounted on the fixed journals 45

and 46 and has alternate panes of red glass, as shown at 52, (see Fig. 3,) and panes of colorless glass or open spaces 53. Within 70 the drum and supported from the fixed journals 45 and 46 is the supporting-strip 54, preferably made in the U shape shown in Fig. 2, so that the lower portion thereof is just clear of the wall of the surrounding rotating drum. 75 This supporting-strip carries two or more incandescent electric lamps, as shown at 55 and 56.

The electric connections for the signaling apparatus are as follows: A feed-wire 57 passes 80 through the hollow journal 45 and connects with the lamp 56, thence passing out through the hollow journal 46 and out of the lantern to the signal-circuit connection 61, the other end of the wire 57 being conducted to ground 85 by being connected to the trolley-pole or in any other suitable manner. The wire 58 also passes through the hollow journal 45 and connects with lamp 55, thence passing out through the journal 46 and being conducted to the 90 ground in any suitable manner. The other end of wire 58 is joined by binding-screws to the wire 59, which runs through the solenoid 48 and thence out to the signal-circuit connection 60. Lamps 55 and 56 are ordinary 95 incandescent electric lamps of proper voltage and have the cut-out keys 62 62, by which they may be thrown out of operation, if desired.

The current-supplying or contact-making apparatus illustrated in Figs. 4 to 6, inclusive, is composed of one or more inverted-U-shaped frames 63 63^a, supported on the trolley-wire 12, but insulated therefrom by the insulating material 64 or other form of insulating hanger. 105 Upon the lower ends of the U-shaped frames are supported contact-rails 65 65^a, which have their outer ends preferably curved each away from the other, so as to guide the trolley-pole 66 in between them and insure a good rubbing contact of said rails 65 65^a against said trolley-pole. To this frame 63 is connected a signal feed-wire 67. Various modifications of this contact-making device may be employed. For instance, in Fig. 7 I show a slab 110 of insulating material 68, which may be of vulcanite or similar substance, supported to one side of the trolley-wire 12 and carrying on its opposite face a metal contact-strip 69, to which the signal feed-wire 67 may be connected by the binding-screw, as shown. In Fig. 8 I have substituted an oval-shaped mass 70, of vulcabeston, into which both the trolley-wire 12 and the metallic contact-strip 71 may be molded. In the construction shown in 115 Figs. 7 and 8 the wheel of the trolley 66 bridges over the space between the trolley-wire and the contact-strip and conveys the current from one to the other.

The mode of operation of my invention is 120 as follows: A trolley-car running along the track, the trolley-pole coming in contact with the rails 65 and 65^a (if the construction shown in Figs. 4 to 6 is used) will deliver a part of

the current derived from trolley-wire 12 to the frame 63 and signal feed-wire 67. If one of the constructions shown in Figs. 7 and 8 is employed, the trolley-wheel itself will bridge over the gap and supply a similar current to the signaling-circuit through wire 67. Suppose the trolley-car to be entering section 6 of the track, as indicated in dotted lines in Fig. 1. The motorman would not have entered said section from turnout 5 unless the signal 34 had shown a white light, indicating that section 6 was unoccupied. Signals 34 and 35 being simultaneous in their action, the position of the trolley-car presupposes that signal 35 also is in the position to show a white light. When the trolley passes the current-supplying point 6^a, current passes from the trolley-wire 12 through the feed-wire 67 to the circuit 16, where it splits, one half passing through the lamp and solenoid in signal-station 34 and through the independent lamp in signal-station 33 and the other half passing through the lamp and solenoid in the signal-station 35 and through the independent lamp in signal-station 36. The effect of this current is to momentarily illuminate the lamps and also to draw up the cores 49 of the solenoids in stations 34 and 35 into the position shown in dotted lines in Fig. 3. When the trolley runs off of the contact rail or strip and connection is broken, the solenoids become dead and the cores drop. The feed-pawl 50^a, engaging the face 47^a of one of the teeth of the ratchet-wheel, forces the drum 51 through one-eighth of a revolution until the stop-pawl 50^b meets the face 47^b of another ratchet-tooth and checks further rotation of the drum. The effect of such action would be, of course, to bring the pane of colored glass 52 opposite the lamps 55 and 56 and the signal will show red at each end of the track-section 6, indicating that said section is occupied so long as the trolley-car is on it. When the trolley-car arrives at the right-hand end of track-section 6 and passes onto turnout 7, its trolley makes connection at 6^b and another current impulse will be sent through the signaling-circuit 16, repeating the before-described operation, which will change signals 34 and 35 from red to white, indicating that track-section 6 is clear. At the same time the illumination of the independent lamp in signal-station 36 will enable the motorman to tell whether or not that signal is showing red or white, and consequently whether or not track-section 8 is occupied. If occupied, he will remain on turnout 7 until the car on section 8 appears, if it is going in an opposite direction, or until the signal 36 changes to white as the car goes off of section 8 onto turnout 9 if the car is going in the same direction. The same operation occurs as each track-section is traversed, the signals guarding that section being set to "danger" as the car goes on to this section and set back to "safety" as the car goes off, and the signals on the adjacent ends of the neighboring track-

sections being illuminated, so that the motorman can always tell the condition of the section ahead of him as he comes onto each turnout. 70

The advantages of my invention consist in its small cost of installation and simplicity of construction and operation and also especially in the great saving in consumption 75 of electric lamps, resulting from the fact that the lamps are only momentarily lighted at the time when the motorman wishes to read the signals instead of being kept continuously aglow both night and day. The system 80 is a complete block system against cars approaching either end of the section and affords the motorman accurate information of the condition of each block and while he is still on the turnout before entering said block. 85 Moreover, but one signal-wire is required for each section of track.

Of course various changes could be made in the details of construction illustrated without departing from the spirit and scope of my 90 invention so long as the relative arrangement of parts shown in the drawings or the principle of operation disclosed in the specification is preserved. More than two lamps may be employed in each signal-station, if desired. 95 Other forms of electric engine for rotating the drum might be substituted or the drum entirely done away with and other means of producing visual indications substituted. The means for obtaining current from the trolley-wire to operate the signals might be changed 100 and the exact location of the signal-stations varied within limits so long as the connection of each signal with the particular section of road which it guards is still clear. 105

Having therefore described my invention, what I claim as new, and desire to protect by Letters Patent, is—

1. In an electric railroad signaling system the combination of a plurality of track-sections, two automatic electrically-operated signals for each section of track located one near each end thereof, and means whereby the passage of a car onto or off of any particular section of track will shift the signals of said 110 section and illuminate the signals of the adjacent ends of the neighboring track-sections.

2. In an electric railroad signaling system the combination of a plurality of track-sections, two automatic electrically-operated signals for each section of track located one near each end thereof, and each consisting of a shifting device and two illuminating devices, an electric circuit for each track-section including the shifting and an illuminating 115 device in the signals for said section and an illuminating device only in the adjacent signals of the neighboring track-sections, and current-supplying devices for said circuit located at either end of that particular track-section and adapted to be operated by a passing car. 125

3. In an electric railroad signaling system, the combination of a plurality of track-sec-

tions, turnouts between said sections, automatically-shifting signals located one near the end of each track-section, and means whereby the passage of a car from section to turnout or from turnout to section will shift the signals near each end of that section and illuminate the signals near the adjacent ends of the neighboring sections.

4. In an electric railroad signaling system, 10 the combination of a plurality of track-sections, turnouts between said sections, signals located one near the end of each section, consisting of a shifting device and two illuminating devices, an electric circuit for each section including the shifting and an illuminating device in the signals near the end of said section and an illuminating device only in the signal near the adjacent ends of the neighboring sections, and current-supplying devices for said circuit located at either end of that particular section and adapted to be operated by a passing car.

5. In an electric railroad signaling system, the combination of a plurality of track-sections, turnouts between said sections, signals located one near the end of each section consisting of a rotating drum of alternately-colored panes of glass, two electric lamps within said drum and electric means for partially 25 rotating the drum in circuit with one of said lamps, an electric circuit for each section including the rotating means and lamp in circuit therewith in the signals near the ends of said section and the independent lamp in each of the signals near the adjacent ends of the neighboring sections, and current-supplying devices for said circuit located at either end of that particular track-section and adapted to be operated by a passing car.

40 6. In an electric railroad signaling system, the combination of a plurality of track-sections, turnouts between said sections, signals located one near the end of each section consisting of a rotating drum of alternately-colored 45 panes of glass, two electric lamps within said drum and electric means for partially ro-

tating the drum in circuit with one of said lamps, an electric circuit for each section including the rotating means and lamp in circuit therewith in the signals near the ends of 50 said sections and the independent lamp in each of the signals near the adjacent ends of the neighboring sections, and current-supplying devices for said circuit located at either end of that particular track-section and 55 adapted to be operated by a passing car, said current-supplying devices consisting of contact-pieces normally insulated from the trolley-wire but adapted to be put in circuit therewith by a bridging action of the trolley 60 of the passing car.

7. In an electric railroad signaling system, the combination of a plurality of track-sections, turnouts between said sections, signals located one near the end of each section consisting of a rotating drum of alternately-colored 65 panes of glass, two electric lamps within said drum and electric means for partially rotating the drum in circuit with one of said lamps, an electric circuit for each section including the rotating means and lamp in circuit therewith in the signals near the ends of said sections and the independent lamp in each of the signals near the adjacent ends of the neighboring sections, and current-supplying devices for said circuit located at either 70 end of that particular track-section and adapted to be operated by a passing car, said current-supplying devices consisting of contact-pieces normally insulated from the trolley-wire but adapted to be put in circuit therewith by a bridging action of the trolley 75 of the passing car, both said contacts connecting with the signaling-circuit at a point between the signals corresponding to the ends 80 of that track-section.

Signed by me at Tamaqua, Pennsylvania, this 22d day of August, 1899.
